UNITED STATES PATENT OFFICE.

RICHARD THORN BECKETT, OF WOODBURY, NEW JERSEY.

MACHINE FOR MOLDING GLASS.

SPECIFICATION forming part of Letters Patent No. 529,694, dated November 27, 1894.

Application filed April 12, 1893. Serial No. 470,025. (No model.)

To all whom it may concern:

Be it known that I, RICHARD THORN BECKETT, of Woodbury, in the county of Gloucester and State of New Jersey, have invented an improvement in Machines for Molding Glass, of which the following is a specification.

My improvement relates particularly to receivers employed in machines for molding glass.

10 In receivers as heretofore constructed, the supporting or operating arms have been attached to the body portion of the mold and at the attaching point the metal of the mold has been thickened to provide the necessary screw hold. It is obvious that a mold having 15 uneven thickness will be unevenly heated and this uneven heating often causes the cracking of the article molded at a point in contact with the portion of the mold having 20 the greatest thickness or lowest temperature. The object of my improvement is to obviate this difficulty.

I will describe a receiver embodying my improvement and then point out the novel 25 features in a claim.

In the accompanying drawings, Figure 1. is a front elevation of a receiver embodying my invention and Fig. 2 is a side elevation thereof.

Referring by reference characters to the 30 drawings, A', A² designate the two sections of the mold consisting of any suitable material such as metal. The sections may have interlocking parts to prevent a possible vertical movement of one section relatively to the 35 other. For this purpose I have shown one of the sections as provided with tongues or lugs

a' and the other with notches or depressions a² into which the tongues or lugs a' engage. At each end the sections are provided with salient parts projected outward beyond the 40 body portion of the mold. To the salient parts supporting bars or plates B', B² are secured, by means of screws a or otherwise. It will be seen by this construction that the supporting bars or plates B', B² are remote from 45 the body portion of the mold and therefore the said body portion has an even thickness throughout and may be evenly heated throughout its whole area. I have shown arms C', C², extended from the bars or plates 50 B', B².

Having described my invention, what I claim is—

In a glass receiver or mold, the combination of a number of sections of substantially uniform thickness throughout, having lateral extensions near their extremities and provided with dowel pins and corresponding recesses upon their superimposed faces, rods or plates attached to said lateral extensions and spanning the intermediate portions of the sections, and supporting or operating bars or links attached to said rods or plates, substantially as specified.

In testimony whereof I have signed my 65 name to this specification in the presence of two subscribing witnesses.

RICHARD THORN BECKETT.
